Primary Examiner — Jennifer L Watkins*(74) Attorney, Agent, or Firm* — Paul J. Backofen, Esq.**CLAIM**

The ornamental design for a tool bag, as shown and described.

DESCRIPTION

FIG. 1 is a left-front perspective view of an open tool bag showing our new design.

FIG. 2 is a perspective view of the internal tool rack for the tool bag of FIG. 1.

FIG. 3 is a detailed left-front perspective view of the tool bag of FIG. 1.

FIG. 4 is a right-rear perspective view thereof.

FIG. 5 is a top plan view thereof.

FIG. 6 is a front elevation view thereof.

FIG. 7 is a right side elevation view thereof.

FIG. 8 is a left side elevation view thereof.

FIG. 9 is a cross-section view of the body of the tool bag of FIG. 6 taken along line 9-9.

FIG. 10 is a top view of the internal tool rack of FIG. 2.

FIG. 11 is a side view of the internal tool rack of FIG. 2, the other side view being a mirror image of FIG. 11.

FIG. 12 is a front elevation view of the internal tool rack of FIG. 2.

FIG. 13 is a top view of the tool tray of the internal tool rack of FIG. 2.

FIG. 14 is a front view of the tool tray of FIG. 13.

FIG. 15 is a side view of the tool tray of FIG. 13; and, FIG. 16 is a perspective view of the tool tray of FIG. 13. The bottom of the tool bag is flat and unornamented. Broken lines in the attached drawings are included for the purpose of illustrating portions of the tool bag and form no part of the claimed design.

1 Claim, 10 Drawing Sheets(56)
